UNITED STATES PATENT OFFICE.

GUSTAV W. WALLIN, OF CHICAGO, ILLINOIS, ASSIGNOR TO GULBRANSEN-DICKINSON COMPANY, OF CHICAGO, ILLINOIS, A CORPORATION OF ILLINOIS.

PNEUMATIC MOTOR.

1,306,159.

Specification of Letters Patent. Patented June 10, 1919.

Application filed June 5, 1915. Serial No. 32,252.

To all whom it may concern:

Be it known that I, GUSTAV W. WALLIN, a subject of the King of Sweden, residing at Chicago, in the county of Cook and State 5 of Illinois, have invented a certain new and useful Improvement in Pneumatic Motors, of which the following is a full, clear, concise, and exact description, reference being had to the accompanying drawings, forming 10 a part of this specification.

My invention relates to pneumatic motors such as are employed upon piano players or player pianos for operating the music-rolls to draw the perforated music-sheet 15 across the tracker-board.

It will be obvious that my device is useful as a motive device wherever a fluid is used as an operating medium, and it will therefore be understood that I cite the above 20 use merely as an instance of the employment of my invention.

My invention is concerned particularly with the valve mechanism for such a motor, and the object of my improvement is to 25 provide valve mechanism which will operate accurately and definitely, which will be simple in construction and arrangement, economical to manufacture, and efficient in its operation. By efficiency in operation I 30 mean particularly the absence of leaks, the absence of undue friction, and the ability to effect the valve changes with the proper degree of suddenness and completeness to secure the greatest power from the motor.

The motive units which I employ are illustrated in the drawings as being bellows or 35 pneumatics, but it will be understood that cylinders and pistons may be equally well employed without varying from the co-operation with the valve mechanism. Just as 40 cylinders and pistons provide expansible compartments, so do bellows or pneumatics, and the equivalency, so far as the valve mechanism is concerned, will be readily apparent.

It will be understood that each of the 45 expansible compartments has a passageway leading therefrom, which, in operation, is to be alternately connected with the atmosphere and with the "power-plant", which 50 may be either a suction-producing means or a pressure-producing means. In other words, my motor may be operated either by applied pressure or applied suction. For 55 convenience of description I shall refer to

the operation as being produced by means of suction, that being the more general usage. It will be understood, then, that each of the channels from the expansible chambers is connected alternately with the 60 atmosphere and with suction to expand and contract the expansible chamber, the movable member necessary to such operation being operatively connected with a crank on the crank-shaft. It is with the disposition 65 of the channels leading from the expansible chambers, and the relation of the valve parts to each other and to these chambers that my invention is concerned, and these features will be more readily understood by 70 reference to the accompanying drawings, in which—

Fig. 1 is a front elevational view of the device of my invention;

Fig. 2 is a rear elevational view thereof, 75 drawn on a slightly smaller scale and including exemplary mechanism for connecting the motor to the driven shafts;

Fig. 3 is a plan view of the device of my invention;

Fig. 4 is a cross-sectional view taken on the plane of the line 4—4 of Fig. 3 and looking in the direction indicated by the arrows;

Fig. 5 is a cross-sectional view through the end-board, which contains the vertical channels;

Fig. 6 is a sectional view taken on the plane of the line 6—6 of Fig. 5 and looking in the direction indicated by the arrows, the line 5—5 of Fig. 6 indicating the plane of 90 section of Fig. 5;

Figs. 7 and 8 are inner face views of the end-board, showing the valve-member in different positions;

Fig. 9 is an outer face view of the end-board, showing the valve-member thereon;

Fig. 10 is a face view of one of the valve-members employed, both valve-members being of the same construction; and,

Fig. 11 is the opposite face view of the 100 valve-member employed.

It will be seen that the general framework of the motor of my invention comprises a vertical supporting-board 12, and end-standard 13, an end-board 14 at the other end, 105 and a top-board 15. These pieces are all firmly secured together and it will be understood that the end-standard 13 and the end-board 14 are properly supported in position, so that the crank-shaft, which will be de- 110

scribed, can be operatively connected with a shaft or shafts to be driven. This general framework supports all the mechanism and contains the air passages, as will be described.

Secured to the back of the top-board 15 and the vertical board 12 is a board 16, slightly inclined from vertical, as illustrated in Fig. 4. A board 17, also slightly inclined from vertical, but in the opposite direction, is disposed opposite the board 16, a wedge-shaped center-piece 18 being clamped between them. The center-piece 18 is made of two parts, and between these two parts, in central position, a hinged member 19 is disposed, the parts 16, 17, 18 and 19 all being firmly held against the back of the top-board 15 by means of screws 20—20.

A movable board 21 hangs from the hinged member 19, as illustrated in Fig. 4, and a bellows cloth 22 joins each of the boards 16 and 17 with the movable board 21, thus forming two bellows compartments 23, 23.

It will now be understood that all the parts indicated by the reference characters 16 to 23, inclusive, combine to form an operative unit, of which units there are three, as indicated in Figs. 1, 2 and 3 at *a*, *b* and *c*. Thus, there are six bellows compartments provided.

In the top-board 15 six channels 24^a, 24^b, 24^c, 24^d, 24^e and 24^f are provided. Each of these channels is connected by a cross channel 25^a or 25^b, etc., whichever the case may be, with a corresponding bellows compartment, the upper channels being connected with the outer bellows, and the lower channels being connected with the inner bellows.

As illustrated in Fig. 4, the inner bellows is connected with its cross channel by means of a direct aperture 26, while the outer bellows is connected with its cross channel by means of a passageway 27, and a channel 28, formed by a hole in the board 17 and closed by a convenient air-tight strip 29.

Leading downwardly in the end-board 14 from the horizontal channels in the top-board, which are extended into the end-board, are the channels 30^a, 30^b, 30^c, 30^d, 30^e and 30^f, respectively.

At the lower end of the channels, on each side of the board 14, a valve-seat 31 is provided, and each valve-seat is provided with three openings, 32^a, 32^b, 32^c, 32^d, 32^e and 32^f, as the case may be, communicating, respectively, with the vertical passageway. The apertures 32^a, 32^b, etc., are the valves, practically, and they are spaced equidistantly from an axis A, and 120 degrees apart.

Mounted upon the axis A in the central portion 33 of the board 14 and in the standard 13, in horizontal position, is the crank-shaft 34, which, as clearly shown in Figs. 1 and 2, is provided with the three cranks

35—35 in respective vertical register with the bellows units *a*, *b* and *c*. The movable member 21 of each of the bellows units is provided with a downward extension 36, to which a connecting member 37 is pivoted at 38, this connecting member being mounted in the bifurcated end of the extension. The other end of the connecting member embraces the crank 35, as indicated at 39. The cranks are disposed 120 degrees apart in position, and the successive impulses which are transmitted to the shaft by the operation of the bellows units will become apparent as this description proceeds.

Within the board 14 and surrounding the crank-shaft 34 is a chamber 40, which is partitioned from the other channels which have been described, as clearly illustrated in Figs. 5 and 6, but which, on the other hand, is connected with a passageway 41, which is adapted to be connected with the source of suction.

As before indicated, the valve-member is illustrated in Figs. 10 and 11. I apply the reference character 42 to the valve-member and it will appear presently that there are two of these members, similarly constructed. The valve-member 42 is provided with an arc-shaped opening spanning an angle of a little more than 120 degrees, this opening being illustrated at 43.

It will now be understood that the valve-member 42 is in the form of a disk adapted to engage the valve-seats 31. The valve-member is provided with a pocket 44 on the side which engages the valve-seats, this pocket being in the form of an arc supplemented by a central portion which, as illustrated, is adapted to coincide with the chamber 40 in the board 14.

The arc portion of the pocket 44, like the opening 43, is of such size as to span a little more than 120 degrees. Furthermore, the pocket 44 and the opening 43 are of such a radius that they may register, as illustrated in the drawings, with one or more of the openings 32^a, 32^b, etc. The fact that only three openings are provided in each seat makes it possible to bring these openings very close to the center. Consequently, the valve disk is small and friction reduced to a minimum.

The fact that the valve mechanism is divided into two portions is also of special importance, since it balances the structure, distributes the friction, makes operation more even, permits of simple distribution of the valve inlets and outlets, and provides maximum surface between the valve inlets and outlets within a minimum of space, this last-named characteristic providing against leaks.

The valve disks 42—42 are capable of longitudinal movement on the shaft 34, and, as illustrated in Figs. 1 and 2, are operatively connected with the shaft for angular movement by means of the dogs 45—45, 130

which are secured to the crank-shaft 34 by means of set-screws 46-46, and which engage in notches 47-47 (Figs. 7 and 10) in the periphery of the disks. Coiled springs 5 of light tension are disposed between the dogs 45-45 and the valve disks 42-42, being illustrated at 48-48, to maintain the valve disks upon their respective seats.

As illustrated in Fig. 2, the crank-shaft 10 34, beyond the standard 13, is provided with a sprocket-wheel 49, which, by means of a sprocket-chain 50, operates the sprocket 51 on one driven shaft 52. By means of a shifting arrangement 53, operated by a lever 54 15 and a link 55, the shaft 34 upon which the shifting means is splined, may be disconnected from the sprocket 49 at 56 and connected with another driven shaft 57 through the intervention of the pinion 58 and the gear 59.

20 The operation will now be clear. When suction is applied at the passageway 41 this suction is transmitted through the chamber 40, the pocket 44 and the valve-seat openings which happen to be in communication 25 with the pocket 44 at that time. The arrangement is such that, as the valve-members turn, one valve-seat opening is being opened into the pocket 44, while the next one is being closed off. This will be evident 30 from Fig. 9. Once in communication with the pocket 44 the valve-seat opening remains in such communication while the valve passes through approximately 120 degrees of its revolution, and, while that valve opening is then closed, the next one is opened.

The same general description applies with reference to the opening 43, except that the exposed valve-seat opening is opened to the atmosphere instead of being connected with 40 suction. The result is that the bellows chambers are successively connected with the suction, remaining in such connection for approximately 120 degrees of the rotation of the crank-shaft, these connections over-lapping somewhat, so that as one bellows cham-

ber is gradually cut out the next one is gradually cut in. I speak of this operation as taking place "gradually," since, obviously, the operation is not instantaneous, but it is sufficiently sudden and effective to get 50 the proper power. At the same time it is sufficiently gradual so that as one bellows chamber is being relieved of the burden of moving the shaft, the next one is taking on the burden correspondingly. It will also be 55 clear that, precisely as each bellows chamber is connected with suction, just so is the opposite bellows chamber connected with the atmosphere, so that, for instance, while the board 21 is moving to the left in response to 60 suction, the air may come in at the right of the board to provide the required pressure. By these successive impulses, as has been described, the shaft 34 is moved with an even torque.

I claim as new and desire to secure by Letters Patent of the United States the following:

In a motor, a plurality of double bellows, each pair having a common movable member, a channel-board, a plurality of channels therein, those for one side of said bellows being in one side of said board and those for the other side of said bellows being in the other side of said board, a second channel-board at right angles to said first named channel board and having similarly arranged channels forming extensions respectively from said first named channels, a crank-shaft mounted in said second board, 70 said second-named channels on one side opening into a valve-seat on their side of the board circularly about said shaft, and the second-named channels on the other side opening on their side of the board circularly 75 about said shaft, and a valve-member mounted on said shaft over each set of openings.

In witness whereof, I hereunto subscribe my name this 2nd day of June, A. D. 1915.

GUSTAV W. WALLIN.
